KNITTING ACCESSORY

Viktoria Beirer, Wattens, Tyrol, Austria

Application April 11, 1949, Serial No. 86,849

4 Claims. (Cl. 66—125)

1

My invention relates to knitting accessories. In many cases, in hand knitting, two differently colored yarns are used for achieving designs of two colors in the knitting. The usual procedure in knitting with two differently colored yarns is to make one or more stitches with one of the colored yarns, then one or more stitches with the second of the colored yarns, and so on, in which case the knitter is faced with the difficulty of keeping the proper yarn in the knitting position. Keeping the differently colored yarns separated and presenting the proper yarn to the knitting position is ordinarily done by manipulating the fingers, which is difficult and not always accurate, causing stitches to be dropped in the knitting process, or causing the wrong colored yarn to be stitched out of its proper turn.

Therefore I have devised a knitting accessory of simple design, to fit over the index finger of the left hand, having articulately mounted arm or lever means in connection therewith for holding and reversing one of the colored yarns in either the forward knitting position or in the rearward, out of the way, position.

A most important object of my invention is to provide a knitting accessory of the above described character having yarn holding eyes formed in ear portions on the body of the knitting device for maintaining one of the differently colored yarns in a normal knitting position.

A further important object of my invention is to provide a knitting accessory having an articulate arm or lever element on the end of which a yarn holding eye is formed for maintaining the second of the differently colored yarns in either a forward knitting position or a rearward non-knitting position.

A further object of my invention is to provide a knitting accessory in which the said ear portions act as stops for the articulate arm element.

A still further object of my invention is to provide a knitting accessory of such simple design as to permit its economical manufacture and production in large quantities.

Other objects and advantages inherent in my invention will be disclosed in the following description and the accompanying illustrations, in which like parts are referred to by like numerals and in which:

Fig. 1 is a side view of my invention showing the articulate arm or lever element in both forward and backwardly tilted positions.

Fig. 2 is a perspective view of my invention shown mounted upon the index finger of a left hand, drawn in phantom lines and showing a

2

piece of knitting with knitting needles held, with two differently colored yarns attached thereto, and properly threaded through the eye portions of my knitting accessory.

5 Fig. 3 is a perspective view of my invention shown mounted on the index finger of a left hand similar to the view in Figure 2, and showing the lever element with its yarn in a rearward position.

10 Fig. 4 is a cross-sectional view of my invention taken substantially on line 4—4 on Fig. 1.

Fig. 5 is a top view of my invention taken looking in the direction of arrows 5—5 on Fig. 1.

15 Fig. 6 is an end view of my invention taken looking in the direction of arrows 6—6 on Fig. 5.

Fig. 7 is an end view of my invention taken looking in the direction of arrows 7—7 on Fig. 5.

20 Referring to the illustrations, my invention is generally designated 8 and consists of a split thimble body element 9, which may preferably taper from its rearward end toward its forward end to better fit over the index finger 22 of a hand 23. The said split thimble body element 9 is longitudinally split at 27 to permit its adjustment to the size of the wearer's index finger.

25 Ear portions 10 and 11 are formed in alignment, one on either end of body element 9. The ear portion 10 acts as a stop for an articulate arm or lever element 15 which is pivoted at 16 to the center of body element 9, in alignment with the said ear portions 10 and 11. The ear portion 11, besides acting as a stop for lever 15, also is provided with an ear portion eye guide 12. A side

30 ear portion 13 is formed at right angles to the plane of ear portion 11 and is centrally located on body means 9. A side portion eye guide 14 is formed in side ear portion 13 in approximately the same plane as ear portion eye guide 12. A lever eye guide 17 is formed on the free end of articulate arm or lever element 15.

35 To use my invention in connection with knitting, the knitting accessory 8 is placed on the index finger 22 of the hand 23, as shown in Figures 2 and 3. The end of a strand of colored

40 yarn, designated 19, is threaded through eye guides 12 and 14. The end of a second, differently colored yarn, 18 is passed over the index finger 22 and knitting accessory 8 and threaded through guide 17 in articulate arm or lever element 15. The knitting 21, together with knitting needle 20 which is inserted in knitted loops 26, is customarily held between the thumb and second fingers of the left hand. The knitting

needle 20' is manipulated by the right hand, not shown.

The other ends 24 and 25 of the differently colored yarns are passed beneath the palm of the hand and toward the knitting supply.

Figure 2 shows the yarn 18, threaded through the guide 17 in articulate lever 15. The said yarn 18 is maintained in the forward or knitting position for the proper number of stitches. When it is desired to knit using the yarn 19, the articulate lever 15 is flipped backwardly to rest against ear 11, as shown in Figure 3. The above described action places the knitting portion of yarn 18 to the rear of the knitting portion of yarn 19, leaving the said colored yarn 19 in the proper forward knitting positions. Thus, by the simple act of flipping articulate arm or lever element 15 from its rest against stop ear portion 10, which is the forward knitting position, to its rest against stop ear portion 11, which is its rearward non-knitting position, the knitting portions of the yarns 18 and 19 are easily and conveniently reversed at will, without the danger of their becoming twisted.

In ordinary knitting, and without the use of my knitting accessory, when knitting with two differently colored yarns, a considerable amount of the attention must be directed toward keeping the proper yarn to be knitted in the forward knitting position. By using my knitting accessory the placement of the knitting portion of the differently colored yarns 18 and 19 is automatically achieved by the simple expedient of flipping lever 15 forwardly or backwardly, thus relieving the knitter of the strain of this constant attention.

My knitting accessory further serves to keep the differently colored knitting yarns from becoming tangled while the knitting is laid away and also prevents stitches from being pulled loose.

Although I have herein described rather succinctly the nature and use of my invention so that persons skilled in the art will have no difficulty apprising themselves of the teachings thereof and, inasmuch as the disclosure is susceptible of various alterations, modifications, and improvements, I hereby reserve the right to all modifications, alterations, and improvements falling within the scope and spirit of my invention, as well as any modifications that are embraced suggestively in the accompanying drawings, and any that may come within the purview of the foregoing description; my invention to be limited only by the appended claims.

Having thus disclosed and revealed my invention, what I claim as new and desire to secure by Letters Patent is:

1. Knitting accessory means comprising, a split thimble body element adapted to be removably secured to a finger of the human hand, a pair of ear portions emanating from the said split thimble body element disposed in transverse relationship, and articulate lever means secured to the outer

surface of the said split thimble body element with its fulcrum in triangulated relationship with the said pair of ear portions, the said articulate lever means and the said ear portions being provided with yarn guide means.

2. Knitting accessory means comprising, a split thimble body element adapted to be removably secured to a finger of the human hand, a pair of ear portions emanating from the said split thimble body element disposed in transverse relationship, and articulate lever means secured to the outer surface of the said split thimble body element with its fulcrum in triangulated relationship with the said pair of ear portions, the said articulate lever means and the said ear portions being provided with yarn guide means, the said yarn guide means on the said ear portions guiding a primary yarn to the knitting operator and the said yarn guide means on the said articulate lever means making optionally and alternately available a secondary yarn.

3. Knitting accessory means comprising, a split thimble body element adapted to be removably secured to a finger of the human hand, a pair of ear portions emanating from the said split thimble body element disposed in transverse relationship, articulate lever means secured to the outer surface of the said split thimble body element with its fulcrum in triangulated relationship with the said pair of ear portions, the said articulate lever means and the said ear portions being provided with yarn guide means, and an ear stop portion disposed in opposed relationship with one ear portion of the said pair of ear portions cooperating with said one ear portion to provide limiting stops for the movement of the said articulate lever means.

4. Knitting accessory means comprising, a split thimble body element adapted to be removably secured to a finger of the human hand, a pair of ear portions emanating from the said split thimble body element disposed in transverse relationship, articulate lever means secured to the outer surface of the said split thimble body element with its fulcrum in triangulated relationship with the said pair of ear portions, the said articulate lever means and the said ear portions being provided with yarn guide means, the said yarn guide means on the said ear portions guiding a primary yarn to the knitting operator and the said yarn guide means on the said articulate lever means making optionally and alternately available a secondary yarn, and an ear stop portion disposed in opposed relationship with one ear portion of the said pair of ear portions cooperating with said one ear portion to provide limiting stops for the movement of the said articulate lever means.

BEIRER, VIKTORIA.
